UNITED STATES PATENT OFFICE.

JOHN S. McCABE, OF BRIDGEVILLE, PENNSYLVANIA.

GAGE-WHEEL ATTACHMENT FOR PLANTERS.

1,228,682.

Specification of Letters Patent.

Patented June 5, 1917.

Application filed July 17, 1916. Serial No. 109,711.

To all whom it may concern:

Be it known that I, JOHN S. McCABE, a citizen of the United States, residing at Bridgeville, in the county of Allegheny and 5 State of Pennsylvania, have invented certain new and useful Improvements in Gage-Wheel Attachments for Planters; and I do declare the following to be a full, clear, and exact description of the invention, such as 10 will enable others skilled in the art to which it appertains to make and use the same.

My invention which relates in general to planters has for its object to provide simply constructed and inexpensive means for gag- 15 ing the depth at which the planting shoes or disks thereof are permitted to enter the earth. With this general object in view, the invention resides in certain novel features of construction and in unique combi- 20 nations of parts to be hereinafter fully described and claimed, the descriptive matter being supplemented by the accompanying drawings which constitute a part of this application and in which:

25 Figure 1 is an enlarged vertical section of the attachment applied to a portion of a corn planter;

Fig. 2 is a perspective view of the at- 30 taching bracket; and

Fig. 3 is a similar view of the bearing sleeve mounted for vertical adjustment in said bracket.

In specifically describing the structure shown in the drawings above briefly de- 35 scribed, similar characters will be employed to designate corresponding parts throughout the several views and reference will be herein made to the numerous elements by their respective indices.

40 Each attachment 1 includes an attaching bracket 2 in the form of a vertically dis- posed cast metal tube having at its lower end a pair of oppositely extending attach- 45 ing ears 3 which are alined transversely of the tube and disposed in the plane of one side thereof. The opposite side of the tubular bracket is formed with an internal longitudinally extending groove 4 and is pref- 50 erably increased in thickness as shown at 5 to prevent said groove from weakening the device. A set screw 6 is threaded through a boss 7 on the thickened portion of the bracket and is adapted to secure in

place a vertically disposed bearing sleeve 8 which is received slidably in the tubular 55 bracket 2.

The sleeve 8 is of greater length than the bracket and is provided on one side with an external longitudinally extending row of teeth 10 on its outer side, said teeth being 60 received in the groove 4 and being adapted for coöperation with the set screw 6. It will thus be evident that by loosening the screw 6 the bearing sleeve 8 may be adjusted 65 vertically to any desired point and then secured in place by again tightening said screw.

A vertical shaft 11 is received rotatably in the bearing sleeve 8 and is provided near its lower end with a cup-shaped collar 12 70 in which the lower end of said sleeve is re- ceived. A cap 13 is disposed on the upper end of the shaft 11 over the bearing sleeve 8 and is secured in place by a pin 14. The lower end of the shaft 11 is forked at 15 75 and is curved rearwardly, a gage wheel 16 being rotatably mounted between the furca- tions of said fork, and is adapted to travel on the surface of the earth.

In use the device 1 is secured to one end 80 of the hopper frame F so that the wheel 16 is spaced outwardly from the shoe S or other earth-working device of the planter being equipped with the improved features. By loosening the set screw 6, the bearing 85 sleeve 8 is now adjusted vertically to the necessary extent to permit the wheel 16 to penetrate the earth to the required amount by the shoe S or other earth-working de- 90 vice after which said screw is tightened. 90 It is of course understood that the planter is to be equipped with a pair of the shoes S or other earth-working devices, each be- ing secured to the frame as above set forth.

I claim:

A device of the class described comprising a tubular bracket having attaching ears thereon, a longitudinal rib on the outer face of said bracket, a longitudinal groove in said rib opening into said tubular bracket, a threaded aperture in said rib to receive a set screw, a tubular sleeve having a toothed rib thereon, said sleeve adapted to be received in said bracket, the toothed rib being received in said groove and being held 105 in adjusted position by a set screw, a gage

wheel pivot shaft extending upwardly through said sleeve, a cup-shaped member on the said shaft extending around the same and adapted to receive the lower end of the 5 said sleeve, and a cap member secured to said shaft near its upper end and adapted to cover the upper end of said sleeve.

In testimony whereof I have hereunto set my hand in the presence of two subscribing witnesses.

JOHN S. McCABE.

Witnesses:

J. WALTER PHILIPS,
EMMA LEA MONTGOMERY.
